UNITED STATES PATENT OFFICE

CLAYTON OLIN NORTH, OF AKRON, OHIO, ASSIGNOR TO THE RUBBER SERVICE LABORATORIES COMPANY, OF AKRON, OHIO, A CORPORATION OF OHIO

HIGHER ALDEHYDE DERIVATIVE OF REACTION PRODUCTS OF ALDEHYDES AND AMINES AND PROCESS OF MAKING SAME

No Drawing. Original application filed March 24, 1923, Serial No. 627,325. Patented February 14, 1928, No. 1,659,151. Divided and application filed March 5, 1926, Serial No. 92,616. Patent No. 1,619,953, dated March 8, 1927. Application for reissue filed December 22, 1927. Serial No. 242,005.

This application is a division of my application Serial No. 627,325, filed March 24, 1923, which application matured into Patent No. 1,659,151, issued February 14, 1928.

5 My invention relates to a process of reacting aliphatic aldehydes higher than formaldehyde with condensation products of aromatic primary amines and aliphatic aldehydes, and particularly reacting acetaldehyde with the condensation product of three mols of acetaldehyde and two mols of aniline. The invention also comprises the new materials obtained.

10 A method of making a compound in which 3 mols of acetaldehyde are combined with 2 mols of aniline is set forth in my Patent No. 1,659,152, granted February 14, 1928. The compound so produced is believed to be in the nature of, or closely related in chemical 15 constitution to, derivatives of tetrahydro-quinoline, which possesses what I choose to call a reactive methyl group, having the property of condensing with one or more molecules of an aldehyde to produce further 20 reaction products.

According to the preferred mode of procedure, acetaldehyde is reacted with aniline to produce a compound in which 3 mols of acetaldehyde are combined with 2 mols of 25 aniline, as claimed in my aforementioned application Serial No. 627,326, and the material so obtained is dehydrated by evaporation at temperatures no higher than 105° C., until the moisture content is substantially reduced.

30 Advantageously the dehydration may be continued until the moisture content is approximately 2%. I have found that this dehydrated compound will react with further 35 aldehyde and in particularly with aliphatic aldehydes higher than formaldehyde, as acetaldehyde and still higher aldehydes. Dehydration of this compound to a substantial extent, at least, is necessary for obtaining 40 optimum yields, the presence of water in substantial proportions apparently being unfavorable to the reaction of aliphatic aldehydes above formaldehyde upon this compound.

45 One example of the ways in which a proc-

ess within my invention can be carried out is the following:

132 parts ($\frac{1}{2}$ mol) of the dehydrated condensation product of acetaldehyde and aniline above described are refluxed with 79.5 parts (approximately 1.8 mols) of acetaldehyde for a period of about 14 or 15 hours at a temperature above the boiling point of the aldehyde, but below the boiling point of water. The refluxing period can be reduced by use of efficient heating means. At the end of the reaction period I preferably discontinue the refluxing, and heat to a temperature of not over 105° C., to evaporate the water and remove the excess aldehyde. In order to avoid frothing and forming I may pass a current of air through the mass while the water is being evaporated. When the water has been practically all removed it is often advantageous to heat at a somewhat higher 50 temperature for a period of about $\frac{1}{2}$ hour or less, but in no case is it advisable to heat above about 115° C. The resinous product so obtained contains approximately 2% of moisture, is hard and vitreous, and can be 55

reduced ground and sifted.

The proportion of ingredients employed in the example set forth when calculated on a molecular basis shows that the final product obtained results from the combination of one molecular proportion of aniline with substantially 3.3 molecular proportions of acetaldehyde. The example, then, discloses the reaction product of an aromatic primary amine with an aliphatic aldehyde containing more than one carbon atom, wherein the product formed results from the combination of the ingredients set forth in the ratio of one molecular proportion of the former to at least three of the latter.

A similar change takes place when acetaldehyde is reacted substantially as disclosed above with the primary aldehyde derivative of anhydro formaldehyde aniline, or with the primary aldehyde derivative of the condensation product formed by the interaction of aliphatic aldehydes, such as formaldehyde or acetaldehyde on primary amines such as aniline, o-toluidine, m-toluidine, p-toluidine, the xylidines, aminocymene, etc. The quan-

tity of aldehyde taken to combine with the aldehyde-amine condensation product is preferably in excess of that actually required to complete the change.

Although in the example given I have specified the use of acetaldehyde on the dehydrated combination product of 3 mols of acetaldehyde and 2 mols of aniline, it is to be understood that my invention is not limited solely to this, but that other similarly constituted materials and compounds may be used. Broadly my invention comprises the manufacture of a compound by condensation reaction of an aliphatic aldehyde above forming aldehyde with the condensation product of aliphatic aldehydes and aromatic primary amines.

I claim:

1. A hard resinous compound formed by the action of acetaldehyde on the reaction product of 3 mols of acetaldehyde with 2 mols of aniline.
2. The process of making a hard resinous compound, which comprises reacting acetaldehyde with the reaction product of 3 mols of acetaldehyde with 2 mols of aniline.
3. A hard resinous compound formed by the action of acetaldehyde on the dehydrated reaction product of 3 mols of acetaldehyde with 2 mols of aniline.
4. The process of making a hard resinous compound, which comprises reacting acetaldehyde with the dehydrated reaction product of 3 mols of acetaldehyde with 2 mols of aniline.
5. A hard resinous compound formed by the action of acetaldehyde on the dehydrated reaction product of acetaldehyde and aniline.
6. The process of making a hard resinous compound, which comprises reacting acetaldehyde on the dehydrated reaction product of acetaldehyde and aniline.
7. A hard resinous compound formed by the action of an aliphatic aldehyde higher than formaldehyde on the dehydrated reaction product of 3 mols of acetaldehyde with 2 mols of aniline.
8. The process of making a hard resinous compound, which comprises reacting an aliphatic aldehyde higher than formaldehyde on the dehydrated reaction product of 3 mols of acetaldehyde with 2 mols of aniline.
9. An aldehyde amine product obtained by the reaction of an aliphatic aldehyde higher than formaldehyde on the reaction product of an aliphatic aldehyde and an aromatic primary amine.
10. The process of making an aldehyde-amine compound, which comprises reacting an aliphatic aldehyde higher than formaldehyde on the reaction product of an aliphatic aldehyde and an aromatic primary amine.
11. The process of making a resinous material, which comprises reacting acetaldehyde and aniline under conditions to produce a re-

action product having substantially 3 mols of acetaldehyde and 2 mols of aniline, refluxing said reaction product together with acetaldehyde, evacuating water, and then cooling and grinding.

12. The process of making a resinous material, which comprises reacting acetaldehyde and aniline in the proportion of substantially 3 mols of acetaldehyde to 2 mols of aniline, evacuating water from the product so obtained, introducing acetaldehyde into said product in the proportion of approximately 79.5 parts of acetaldehyde to 132 parts of said product, refluxing the mixture at a temperature above the boiling point of acetaldehyde and below the boiling point of water for several hours, evacuating water, then further heating at a temperature not to exceed 115° C., and then cooling and grinding.

13. A hard resinous compound formed by reacting approximately 79.5 parts of acetaldehyde with approximately 132 parts of the dehydrated reaction product of 3 mols of acetaldehyde and 2 mols of aniline.

14. The process of making a hard resinous compound, which comprises reacting approximately 79.5 parts of acetaldehyde with approximately 132 parts of the dehydrated reaction product of 3 mols of acetaldehyde and 2 mols of aniline.

15. The process of preparing the aldehyde derivative of the reaction product of an aldehyde and an aromatic primary amine which comprises reacting the amine with an excess of the aldehyde in a plurality of stages substantially as described.

16. The process of preparing the acetaldehyde derivative of the reaction product of acetaldehyde and aniline which comprises reacting aniline with an excess of acetaldehyde in a plurality of stages, substantially as described.

17. The process of preparing the aldehyde derivative of the reaction product of an aldehyde and an aromatic primary amine which comprises reacting one molecular proportion of the amine with not less than three molecular proportions of an aldehyde.

18. The process of manufacturing the aliphatic aldehyde derivative of the reaction product of an aliphatic aldehyde and an aromatic primary amine which comprises reacting one molecular proportion of the amine with more than three molecular proportions of a single aldehyde.

In testimony whereof I hereunto affix my signature.

CLAYTON OLIN NORTH.
